(57) **CLAIM**

We claim the ornamental design for a toilet seat hinge, as
shown and described.

DESCRIPTION

FIG. 1 is a first perspective view of a toilet seat hinge
according to one embodiment.

FIG. 2 is a second perspective view of the toilet seat hinge
of FIG. 1.

FIG. 3 is a third perspective view of the toilet seat hinge of
FIG. 1.

FIG. 4 is a fourth perspective view of the toilet seat hinge of
FIG. 1.

FIG. 5 is a first side view of the toilet seat hinge of FIG. 1.

FIG. 6 is a second side view of the toilet seat hinge of FIG.
1.

FIG. 7 is a third side view of the toilet seat hinge of FIG. 1.

FIG. 8 is a fourth side view of the toilet seat hinge of FIG.
1.

FIG. 9 is a top view of the toilet seat hinge of FIG. 1; and,
FIG. 10 is a bottom view of the toilet seat hinge of FIG. 1.
Portions of the toilet seat hinge shown in evenly-spaced
broken lines are included for the purpose of illustrating
environment and form no part of the claimed design.

Dash-dot broken lines are included for the purpose of
illustrating a boundary of the claimed design and form no
part of the claimed design.

1 Claim, 10 Drawing Sheets
